UNITED STATES PATENT OFFICE.

LEWIS DEGEN, OF PASADENA, CALIFORNIA.

AUXILIARY SIGNAL SYSTEM.

1,267,987.

Specification of Letters Patent. Patented May 28, 1918.

Application filed May 11, 1917. Serial No. 167,910.

To all whom it may concern:

Be it known that I, LEWIS DEGEN, a citizen of the United States, residing at Pasadena, in the county of Los Angeles, State of California, have invented new and useful Improvements in Auxiliary Signal Systems, of which the following is a specification.

This invention relates to a signaling system especially adapted for sending and receiving fire alarms, and pertains particularly to a signal system having sub-stations and auxiliary means located remote from the substation for actuating the sub-station signal sending mechanism.

15 It is an object of this invention to provide means whereby a call indicating trouble in the auxiliary means may be sent over the wires which carry the fire alarm signal, and whereby the alarm will be received at the central station and identified as a trouble call.

I have illustrated the embodiment of my invention in the accompanying diagrammatic drawing.

25 Referring more particularly to the drawing, a sub-station box is indicated by 1. Within the box is disposed a character wheel 2, and a lever 3 cooperating therewith for opening and closing the main circuit. Lever 30 3 is in contact with one member of a switch 4 which is disposed in series in the main circuit. The box may include the usual spring motor or any suitable mechanism for rotating the character wheel, and also means for 35 tripping the box and rendering the character wheel effective in sending signals. The box mechanism is well known in the art, and as it does not form a feature of my invention it is not illustrated or described in detail 40 herein.

The terminals of switch 4 are connected by conductors 5 and 6 to binding posts 7 and 8. Binding posts 7 and 8 are connected by conductors 9 and 10 to posts 11 and 12. The 45 main line wires 13 and 14 are connected to posts 11 and 12, and extend to the central station. Suitable signal receiving apparatus is located at the central station.

The apparatus shown herein is of simple

form, but may be elaborated upon to provide all of the apparatus which is commonly used at such central station. It is essential that there be a battery 15 which is a source of current for the main line, a sensitive relay 16 and a non-sensitive relay 17. The sensitive relay 16 controls a circuit 18 having therein apparatus for receiving trouble calls. The non-sensitive relay 17 controls a circuit 19, in which there is apparatus for receiving the fire alarm signals. The circuit just described is one which is common in fire alarm systems. Normally the circuit is closed and the current flows therethrough. This current is usually maintained at about 100 milli-amperes. Upon opening the circuit the current strength falls to zero, and the non-sensitive relay 17 is actuated causing the opening and closing of the circuit 19 and actuation of the alarms signal receiving apparatus.

70 The signal sending mechanism is tripped by means of a trip lever 20 having a projection 21 which engages a recess in a wheel 22. The mechanism may be tripped in the box by pulling the lever 23, which is shown 75 in section, thereby lifting the lever 20, raising the projection 21 out of the recess and permitting the wheel 22 to rotate: this starts the character wheel to rotating. The lever 20 is extended beyond its pivot point and 80 its end is disposed in the path of a pin 24, which extends laterally from the worm wheel 25. Worm wheel 25 is engaged with a worm 26, the latter being fixed to a shaft 27. Shaft 27 is operated by a motor 28. 85 The motor is controlled by an auxiliary system so that when it is set into operation the rotation of worm 26 will cause gear 25 to rotate and pin 24 to contact lever 20, lifting the latter and tripping the box.

90 Shunted across the switch 4 of the signal sending mechanism is a carbon resistance 29. One terminal of the resistance is connected to binding post 7, and the other terminal to one side 30 of a switch. The movable blade 95 of the switch is connected to binding post 8. When the switch is closed the resistance 29 is shunted across the switch 4. When the

carbon resistance 29 is shunted across the switch 4 the opening and closing of the switch will cause a variation in current flow, and the resistances are so adjusted that the 5 current flow will vary from 90 to 100 milli-ampères.

A pivoted armature 31 has one end in contact with the movable blade of switch 30 so that its movement will make and break 10 the shunt circuit. A two pole relay is provided to actuate the armature 31. The winding of one pole 32 is so arranged in the circuit that when energized the armature 31 will be lifted opening switch 30, 15 thereby opening the shunt circuit. The pole 33 is so wound that when energized it will attract armature 31 and close the switch 30, thereby closing the shunt circuit.

One terminal of pole winding 32 and one 20 terminal of pole winding 33 are joined and connected by conductor 34 to one terminal of motor 28. One terminal of the pole winding 32 is connected by a conductor 35 to the positive side of an auxiliary battery. One 25 terminal of pole winding 33 is connected by a conductor 36 to the positive side of auxiliary battery. A terminal of motor 28 is connected by a conductor 37 to the negative side of the auxiliary battery. Con- 30 ductor 37 is a common return for current flowing in conductors 35 and 36.

Current for sending in a fire alarm from the auxiliary system passes through conductor 35. In circuit with conductor 35 is a 35 resistance 38; shunted across resistance 38 is a circuit having a relay switch 39 therein. The relay switch is normally held open by a tension spring. The resistance 38 is connected to the positive side of a battery 40. 40 The other side of battery 40 is directly connected to conductor 37. Conductor 36 has in circuit therewith a resistance 41 which is connected to the positive side of battery 40. Shunted across resistance 41 is a circuit hav- 45 ing a relay switch 42. Switch 42 is normally held open by current flowing in the circuit.

If switch 42 is closed the resistance in circuit with conductor 36 is reduced; and increased current flows through pole winding 33, through motor 28, and back to the negative side of the battery. Energization of magnet winding 33 causes the armature 31 to move and close the switch 30 and the 55 shunt circuit across the signal sending means, and place the carbon resistance 29 in shunt across switch 4. At the same time current flowing through motor 28 causes the latter to start and trip the box. The switch 60 4 opens and closes the main circuit, the current varying from 90 to 100 milli-ampères. Such variation of current will not effect the non-sensitive relay but does effect the sensitive relay: therefore, circuit 18 is opened

and closed, thereby indicating on the signal 65 mechanism associated therewith that there is trouble at the sub-station 1.

Assuming that the auxiliary circuit is in normal condition, switch 42 being open: switch 39 is now closed; the resistance in 70 circuit with conductor 35 will be decreased and current will flow through pole winding 32 energizing the latter. This causes armature 31 to lift and the movable blade of switch 30 to open placing the carbon resist- 75 ance 29 out of circuit. Current also flows along the common return through motor 28 and conductor 37 to the negative pole of the battery. This causes the motor armature to rotate, thereby rotating gear 25 and tripping 80 the signal sending mechanism; switch 4 opens and closes the circuit, and the non-sensitive relay is effected by variation of current from zero to 100 milli-ampères; circuit 19 is opened and closed at the central station 85 and a fire alarm indicated on the receiving mechanism.

Relay switches 39 and 42 in the auxiliary mechanism are actuated in the following manner: A magnet 43 controls the switch 42 90 and has a winding which is in circuit with a switch 44 and battery 45, and magnet winding 46. Switch 39 is controlled by a magnet 46 having a magnet winding connected in series with the magnet winding 43, switch 44 95 and battery 45. Switch 44 does not open and close the circuit but bridges a resistance 47. Normally there is current flowing through the magnet windings 43 and 46, the circuit being normally closed. When the 100 switch 44 is closed the resistance of the circuit is decreased and sufficient current flows to cause the closure of switch 39. This trips the sub-station mechanism to send in a fire alarm.

If a break in wiring occurs in the auxiliary local circuit, magnet 43 will be de-energized and switch 42 will close due to the tension spring connected thereto, thereby tripping the box and shunting the carbon resistance 110 39 across the switch 3. A trouble call will then be sent over the main line.

I have shown particular mechanism for operating the two pole relay in the substa- 115 tion box. I have shown this mechanism merely for the purpose of illustrating the invention. Automatic devices of various kinds may be substituted and the auxiliary circuit changed to suit circumstances.

What I claim is:

1. In a signaling system, the combination of a normally closed main circuit extending from a central exchange, said main circuit including a source of current, non-sensitive signal receiving apparatus, sensitive signal receiving apparatus, and a sub-station; signal sending means at said sub-station for opening and closing the circuit, whereby the 125

non-sensitive receiving apparatus is effective: a shunt circuit disposed across said signal sending means including a resistance and switch means for opening and closing 5 said shunt circuit: and automatic means to operate said switch means.

2. In a signaling system, the combination of a normally closed main circuit extending from a central exchange, said main circuit 10 including a source of current, non-sensitive signal receiving apparatus, sensitive signal receiving apparatus, and a sub-station; signal sending means at said sub-station for opening and closing the circuit, whereby the 15 non-sensitive receiving apparatus is effective; a shunt circuit disposed across said signal sending means including a resistance and switch means for opening and closing said shunt circuit: and automatic means to 20 operate said switch means and to render said signal sending means effective.

3. In a signaling system, the combination of a normally closed main circuit extending from a central exchange, said main circuit 25 including a source of current, non-sensitive signal receiving apparatus, sensitive signal receiving apparatus, and a sub-station; signal sending means at said sub-station for opening and closing the circuit, whereby the 30 non-sensitive receiving apparatus is effective: a shunt circuit disposed across said signal sending means including a resistance and switch means for opening and closing said shunt circuit: an auxiliary circuit including 35 electro-motor means to operate said switch means, and means for controlling the actuation of said electromotor to either open or close said switch means.

4. In a signaling system, the combination 40 of a normally closed main circuit extending from a central exchange, said main circuit including a source of current, non-sensitive signal receiving apparatus, sensitive signal receiving apparatus, and a sub-station; signal sending means at said sub-station for 45 opening and closing the circuit, whereby the non-sensitive receiving apparatus is effective: a shunt circuit disposed across said signal sending means including a resistance and switch means for opening and closing 50 said shunt circuit: an auxiliary circuit including electro-motor means to operate said switch means and having three wires so connected that current flowing through one of 55 said wires will operate said electro-motor to open said shunt circuit, and current flowing through another wire will operate said electromotor to close said shunt circuit.

5. In a signaling system, the combination 60 of a normally closed main circuit extending from a central exchange, said main circuit including a source of current, non-sensitive signal receiving apparatus, sensitive signal receiving apparatus, and a sub-station; sig-

nal sending means at said sub-station for 65 opening and closing the circuit, whereby the non-sensitive receiving apparatus is effective: a shunt circuit disposed across said signal sending means including a resistance and switch means for opening and closing 70 said shunt circuit: electromotor means to operate said switch means so as to close or open said shunt circuit, an auxiliary circuit including the aforesaid electromotor means and a trip electromotor to render said signal 75 sending means effective, said auxiliary circuit having three wires so connected that current flowing through one of said wires will operate said electromotor means to open said shunt circuit and current flowing 80 through another wire will operate said electromotor means to close said shunt circuit, said trip electromotor being in circuit with the third wire so as to be operated by a flow of current in either of said other wires. 85

6. In a signaling system, the combination of a normally closed main circuit extending from a central exchange, said main circuit including a source of current, non-sensitive signal receiving apparatus, sensitive signal 90 receiving apparatus, and a sub-station; signal sending means at said sub-station for opening and closing said main circuit, whereby the non-sensitive receiving apparatus is effective: a shunt circuit disposed across said 95 signal sending means including a resistance and switch means for opening and closing said shunt circuit: a two pole relay for operating said switch, one winding thereof when energized causing said switch to open 100 and the other winding thereof when energized causing said switch to be closed, an auxiliary circuit including said relay and having three wires, one of said wires being a common return, said relay windings being so connected in said auxiliary circuit that on flow of current through one of said wires one winding will be energized and on flow of current through another the other winding of the relay will be energized. 105

7. In a signaling system, the combination of a normally closed main circuit extending from a central exchange, said main circuit including a source of current, non-sensitive signal receiving apparatus, sensitive signal 115 receiving apparatus, and a sub-station; signal sending means at said sub-station for opening and closing said main circuit whereby the non-sensitive receiving apparatus is effective: a shunt circuit disposed across said 120 signal sending means including a resistance and switch means for opening and closing said shunt circuit: a two pole relay for operating said switch, one winding thereof when energized causing said switch to open 125 and the other winding thereof when energized causing said switch to be closed, an auxiliary circuit including said relay and a

trip electromotor to render said signal sending means effective, said auxiliary circuit having three wires, one being a common return, said relay windings being so connected 5 in said auxiliary circuit that on flow of current through one of said wires one winding will be energized and on flow of current through another of said wires the other

winding of said relay will be energized, said trip electromotor being in circuit with the 10 third wire so as to be operated by flow of current in either of said other wires.

In witness that I claim the foregoing I have hereunto subscribed my name this 23rd day of April, 1917.

LEWIS DEGEN.
